MOBILE BASE FOR A CONVECTION OVEN

Robert E. Lee, Huntington, Ind., assignor to Lincoln
Manufacturing Company, Inc.

Filed Mar. 7, 1973, Ser. No. 338,665

Term of patent 14 years

Int. Cl. D12—02

U.S. Cl. D12—31

FIG. 1

FIG. 2

FIG. 3

FIG. 4

FIG. 1 is a perspective view of a mobile base for a convection oven showing my new design;

FIG. 2 is an end elevational view thereof;

FIG. 3 is a perspective view of the bottom thereof; and FIG. 4 is a side elevational view thereof.

The undisclosed side and end are mere images of the side and end shown.

I claim:

The ornamental design for a mobile base for a convection oven, substantially as shown and described.
